Attorneys.

UNITED STATES PATENT OFFICE.

THOMAS W. GREEN, OF WESTMONT, NEW JERSEY, ASSIGNOR TO THOMAS WILBRAHAM
GREEN ENGINEERING CO., OF PHILADELPHIA, PENNSYLVANIA, A CORPORATION
OF PENNSYLVANIA.

SUCTION CLEANER.

Application filed October 9, 1922. Serial No. 593,197.

My invention relates to vacuum sweepers.

The main object of my invention is to provide an improved sweeper adapted to easy and inexpensive manufacture and efficient operation.

A further purpose is to provide improved connections whereby the fan of a non-electric sweeper may be thrown into gear and operated by the forward motion of the 10 sweeper along the floor and disconnected from driving connection with the wheels of the sweeper as soon as the sweeper stops, permitting return of the sweeper without reversal in the direction of the fan.

15 A further purpose is to provide an improved drive between the shaft of the sweeper wheels and the fan and brush.

Further purposes will appear in the specification and claims.

20 I have preferred to illustrate my invention by one main form only, selecting the form because of its value in illustrating the principles of my invention.

Figure 1 shows in a sectional elevation of 25 the form selected.

Figure 2 is a section through line 2—2 of Figure 1.

Figure 3 is a section through line 3—3 of Figure 1.

30 Figure 4 is a section through line 4—4 of Figure 1.

Figure 5 is a fragmentary section upon line 5—5 of Figure 1.

In all the drawings like numbers refer to 35 like parts.

Describing my invention in illustration and not in limitation:—

In the form shown in the figures the shoe and other parts are preferably made of cast 40 metal rather than of pressed metal. The fan is of the general type disclosed and claimed in my Patent No. 1,350,724 having radial inlet ports and discharge ports. The supporting wheels 112 and 113 are carried 45 upon a vertical pivot 114. The fan 115 is placed directly over the shoe and the fan shaft 116 extends down into the shoe through bearing 117 rigid with the shoe. The fan is shown as provided with radial 50 inlets 115' and circumferential outlets 115''. The shaft carries a worm 118 to engage the worm gear 119 upon the shaft 120 of the rotary brush 121. The shaft 120 is sup-

ported in bearings 122 and 123 rigid with the casing of the shoe. The discharge duct 55 from the fan comprises lateral portions 124 and 125 connected together above the fan through a duct 126 to a discharge port 127 leading to the dust bag which is not shown, being no part of the invention.

A single casting 128 forms the shoe and lower and side portions of the fan casing and the pillow-block bearings 129 and 130 for the vertical pivot 114 of the wheels 112, 113, as well as the lower portion 131 of the 60 gear casing.

The vertical shaft 116 of the fan and worm passes through the bearing 132 of the casting 133 and at its upper end carries the spur gear 134 in mesh with the large gear 135 that is rigidly and axially connected with the small spur 136 which through the idler spur 137 is driven by the large gear 138 upon the vertical pivot 114 of the wheels.

One of the large wheels drives the spur gear 138 through shaft 139, disc 140, latch 141 carried by the disc, an annulus 142 engaged by the latch, gear 143 rigid with the annulus and a hollow gear 144 connected by a hollow sleeve 145 with gear 138.

Handle 146 is pivoted in gears 147 upon a fitting 148 about pivot 114 and the fitting is secured in angular position with respect to this pivot 114 by thumb screw 149, permitting the handle to be set angularly with 85 respect to the body of the cleaner. A lug 41 upon the top of the cover 42 carries a thumb screw 43 adapted to lock the vertical pivot in any desired position to prevent turning.

The construction is suited to easy manufacture from a very few castings only.

In operation the direction of the wheels 112 and 113 is controlled by the shaft 114 fixed at its bottom in the bearing 150 for the 95 axle for these wheels as best seen in the fragmentary view of Figure 5. Meantime the fan mechanism is driven through gear 138 by which also the brush is driven.

Variations and modifications will doubtless become evident to others skilled in the art to meet individual whim or particular need, and it is my desire to claim all such variations and modifications in so far as they fall within the reasonable spirit and 105 scope of my claims.

Having thus described my invention, what I claim as new and desire to secure by Letters Patent is:—

1. In a suction sweeper, a pair of driving wheels, a horizontal shaft connecting the wheels, a gear upon the shaft, a clutch between one of the wheels and the gear, a bearing for the shaft, a vertical shaft rigid with the bearing, two rigidly connected gears rotatably mounted on the vertical shaft, the lower meshing with the first named gear, a handle connected to the vertical shaft to swing the horizontal shaft about a vertical axis, a shoe adapted to be supported upon the floor, a fan above the shoe and connections between the upper gear upon the vertical shaft and the fan to drive the fan.
2. In a suction sweeper a horizontal shaft, driving wheels thereon, a vertical shaft with which the horizontal shaft swings bodily, gearing rotatably mounted on the vertical shaft, a handle connected with the vertical shaft to swing horizontally, a shoe, a fan and driving connections between the fan and the gearing on the one side and between the gearing and the driving wheels on the other.
3. In a suction cleaner, a casing, supporting wheels to roll on a floor, a horizontal shaft upon which the wheels are mounted, a sleeve thereabout, a vertical pivot rigid with the sleeve, a bearing therefor, a member rigidly connected to the end of the pivot, a handle horizontally pivoted to the member, a lug on the casing and close to the member, and a screw therethrough adapted to lock the member relatively to the lug.
4. In a suction sweeper, a roller supported casing having openings at the top forming fan inlets, a fan having blades sweeping past said inlets and turning about a vertical axis, walls circumferentially enclosing portions of the fan, apertured for outlets and

forming a distributing outlet channel at the sides connected with said outlets, a vertical driving shaft for said fan, a driving gear at the upper end of said shaft, bearings for the shaft above the fan, a pair of driving wheels and clutch connection from said driving wheels for driving the gear upon the vertical shaft.

5. In a suction sweeper, a roller-supported casing having inlet openings at the top forming fan inlets, a fan having blades sweeping past said inlets and turning about a vertical axis, walls circumferentially enclosing portions of the fan, apertured for outlets and forming a distributing outlet channel at the sides connected with said outlets, a vertical driving shaft for said fan, a driving gear at the upper end of the shaft, bearings for the shaft above the fan, a bearing for the lower end of the shaft, a worm upon the shaft below the fan, a worm gear connecting with the worm, a rotary brush, a shaft therefor directly driven by the worm gear, a pair of driving wheels and clutch connection from said driving wheels for driving the gear upon the vertical shaft.

6. In a suction sweeper, a pair of guiding wheels, a horizontal shaft connecting the wheels, a gear upon the shaft, a bearing for the shaft, a vertical shaft rigid with the bearing, two rigidly connected gears rotatably mounted on the vertical shaft, the lower meshing with the first named gear, a handle connected to the vertical shaft to swing the horizontal shaft about a vertical axis, a shoe adapted to be supported upon a floor, a fan above the shoe, connections between the upper gear upon the vertical shaft and the fan to drive the fan and clutch mechanism permitting one of the wheels to move independently of the other.

THOMAS W. GREEN.
